MAXIMILIAN M. GOLDBERG, OF DAYTON, OHIO, ASSIGNOR OF ONE-HALF TO V. F. KING,
OF DAYTON, OHIO.

RECORDING DEVICE FOR TELEPHONE PAY-STATIONS.

1,126,751.

Specification of Letters Patent.

Patented Feb. 2, 1915.

Application filed October 18, 1913. Serial No. 795,900.

To all whom it may concern:

Be it known that I, MAXIMILIAN M. GOLDBERG, a citizen of the United States, residing at Dayton, in the county of Montgomery and State of Ohio, have invented certain new and useful Improvements in Recording Devices for Telephone Pay-Stations, of which the following is a specification, reference being had therein to the accompanying drawing.

This invention relates to recording devices for telephone pay stations and is designed more particularly to compute and print, or otherwise produce a removable record of, the amount of money deposited in said station in a given period of time as, for example, the interval between two visits of the collector.

It is a further object of the invention to provide means to positively actuate the recording mechanism, thus avoiding the uncertainty of operation which exists where the weight of the coin alone is utilized for operating the counting mechanism; to utilize the coin in forming the initial connection between the positively actuated means and the recording mechanism; to so arrange the mechanism that the calling party must put the positively actuated mechanism in a condition to operate the counter before he can call the central operator; to provide improved devices under the control of the central operator for depositing the coin in the money receptacle if the connection asked for is established or returning the same to the calling party if the connection is not established.

It is also an object of the invention to control the printing mechanism by the operation of the door leading to the money receptacle in such a manner that a record must of necessity be printed before the door can be opened far enough to enable the money to be removed from the receptacle; and further to control the resetting of the counters by the said door, thus preventing the manipulation of the counters before a record has been printed therefrom.

In the accompanying drawings, Figure 1 is a side elevation of the mechanism with the casing broken away; Fig. 2 is a sectional view taken on the line $x-x$ of Fig. 3; Fig. 3 is a sectional view taken on the line $y-y$ of Fig. 2; Fig. 4 is an elevation of that side 55 of the device opposite that shown in Fig. 1

with the casing broken away; Fig. 5 is a sectional view taken on the line $w-w$ of Fig. 3 with the magnets broken away; Fig. 6 is a detail of the cams for releasing the counter gears; and Fig. 7 is a detail of the resetting device.

In these drawings I have illustrated one embodiment of my invention and have shown the same applied to an ordinary telephone pay station and adapted to handle 65 coins of a single denomination only but it will be understood that the invention is capable of application to stations or mechanisms of various kinds and by making the necessary additions can be adapted to handle 70 coins of different denominations.

In carrying out the present form of the invention I have mounted the mechanism upon a frame comprising a back member 1 constituting the back of a casing 2 which 75 incloses the mechanism with the exception of the push lever to be actuated by the calling party. The main frame comprises in addition to the back member 1 frame members 3 which extend into the casing and 80 form supports for the various parts of the mechanism. It is desirable that the coin be deposited in the machine before the central operator is called and to this end I have provided means for so controlling the calling signal that this signal cannot be operated except when there is a coin in proper position within the machine. The calling signal may be of any suitable kind but preferably comprises the usual signal circuit extending from the instrument to the switch board at the central station where it is connected with a lamp which will be illuminated when the circuit is closed. Inasmuch as this circuit is of a well known construction and forms no part of the present invention I have not illustrated the same but have shown only the circuit breaker and closer which comprises two spring contacts 4 and 5. The contact member 5 is resiliently mounted and is adapted to move toward and away from the contact member 4, this movement being imparted to the member 5 by means of a lever 6 pivotally mounted upon the main frame at 7 and having one arm extending upwardly along the contact member 5 and provided with a projection or roller 8 to engage that member when the lever is rocked about its axis. The lever has a second arm 9 adapted to be engaged 100

105 with the casing broken away; Fig. 2 is a sectional view taken on the line $x-x$ of Fig. 3; Fig. 3 is a sectional view taken on the line $y-y$ of Fig. 2; Fig. 4 is an elevation of that side 55 of the device opposite that shown in Fig. 1

5 by a catch 10 and locked in such a position as to hold the lever in an inoperative position relatively to the contact member 5, thus making it impossible to operate the signal 10 by closing the circuit. The catch 10 constitutes one arm of a bell crank lever which is pivotally mounted at 11 and the other arm of which carries a pin 12 extending through a slot 13 into the lower portion 15 of a coin chute 14, the upper end of which communicates with an opening 15 in the casing 2. The latch is held normally in engagement with the arm 9 of the locking lever by a spring 16, the tension of which is so 20 slight that the weight of a coin dropping through the chute 14 will overcome the tension of the spring and the frictional contact between the latch and the arm 9 and disconnect these parts, thereby leaving the 25 lever 6 free to move under the influence of an actuating spring 17 which moves it into engagement with the contact member 5 and carries that member into contact with its co-operating member 4, thereby closing the 30 circuit and operating the signal when a coin has been deposited in the chute 14.

Counting mechanism of any suitable kind is provided for computing the value of the coins deposited in the chute 14 and accepted 35 by the central operator, as will be herein-after described. In order to secure a positive operation of the counting mechanism I prefer that the actuating device therefor should be operated by power mechanism of 40 some kind, such, for example, as a spring. While it is possible to utilize a spring which could be wound and would thus operate the counting mechanism a number of times I prefer to utilize a simple coil spring and 45 to provide means whereby the same will be placed under tension, or put in condition to operate the counters, by the calling party. To this end I have provided means for normally closing the chute 14 to prevent 50 the same from receiving a coin and have connected the device which must be operated by the calling party to open the chute with the spring so that the act of opening the chute to permit of the deposit of the coin 55 will place the spring under tension. In the present form of the device the closure for the chute comprises a plate 18 carried by the forward end of a lever 19 and extending across the upper end of the chute 60 14, between the end of the chute and the opening 15 in the casing, as shown in Fig. 2. The lever 19 is pivotally supported at 20 in the rear part of the casing and has a downwardly extending portion 21 which 65 is connected by a pin and slot connection with one arm of a bell crank lever 22 mounted on a stud 23 journaled in the lower portion of the frame, projecting through the casing and having secured to the outer end thereof a push lever 24 arranged at one

side of the casing 2 and having at its upper end a plate marked with the word "Push", as indicated at 25. When the push lever 24 is moved rearwardly motion will be transmitted to the lever 19 carrying the cut-off plate 18 and this plate will be moved downward out of alignment with the chute 14, thereby opening the chute and permitting a coin to be deposited therein to operate the calling signal as above described. The bell crank lever 22, which is mounted on the stud 23, has its lower arm provided with a projection or roller 26 which extends beneath a foot 27 projecting from an arm 28 pivoted at 29 on the lower part of the frame and provided with a heel 30 connected with the lower end of a coiled spring 31, the upper end of which is secured to the upper portion of the frame. Thus the movement of the push lever will also actuate the arm 28 to place the spring 31 under tension. I prefer to lock the arm 28 in a position to retain the spring under tension after the lever 24 and arm 19 have been released, these parts when released being returned to their normal positions by a spring 32 connected to the lever 19. To accomplish this I have provided the arm 28 at its upper end with a projection, such as a roller 33, and have mounted on the upper portion of the casing a detent lever 34 which has one end pivotally supported at 35 and has its other end arranged to be moved into and out of the path of the projection 33 on the arm 28. A spring 36 holds the lever 34 normally in its lowermost position and when the arm 28 is moved rearwardly the projection 33 will engage the lower edge of the lever 34 and elevate the same to permit the projection to pass. As soon as the projection has passed the lever 34 will move into its normal position in the path of the projection and thus lock the arm in a position to maintain the tension of the spring 31 until it is desired to utilize the same for the operation of the counter.

When the signal has been operated on the switch board at the central station the operator inquires as to the connection desired by the calling party. If the connection is made the coin is accepted and deposited in a coin receptacle, indicated at 37 in the lower part of the casing 2. If the connection cannot be made the coin is returned to the calling party and serves as notice that the connection requested cannot be made. Consequently, it is necessary that the coin when first deposited in the chute 14 and after it has caused the actuation of the calling signal shall be retained in such a position that it can be diverted in either one of two directions at the will of the operator at the central station. In the present mechanism this is accomplished by causing the coin, which is indicated at 38, in Fig. 2, to

engage a projection or pin 39 on the disk 40 which is rigidly mounted on a shaft 41. The coin engages the pin 39 immediately after it has released the catch 10 and is supported between the pin 12 on the lever carrying the catch and the pin 39 on the disk. In this position the coin is arranged in the path of the rear edge of the arm 28, which is connected with the spring 31, and when released this arm will be moved into engagement with the coin and through the medium of the coin rotary movement will be imparted to the disk 40 which is connected with the counting device, as will be herein-after explained. To release the arm 28 to permit the spring 31 to act I preferably provide an electro-magnet, the armature of which is arranged to actuate the lever 34 and which magnet can be energized by the central operator. In the present machine I have provided a polarized magnet comprising two coils 42 and 43. Arranged above these coils is an armature 44 pivotally supported between its ends so that when current is sent through the polarized magnet in one direction to energize one coil, one end of the armature will move downward and the other up and when the other coil is energized the armature will move in the opposite direction. The lever 34 has a lug or laterally extending projection 45 which extends above one end of the armature and is so positioned that when the magnet is so energized that the opposite end of the armature is attracted the first-mentioned end will engage the projection 45, elevate the lever 34 and thus release the arm 28 and permit the spring 31 to act. Preferably, the magnet is placed in the calling circuit and is so wound that the light current utilized for operating the calling signal will not energize the same sufficiently to attract the armature and when the central operator wishes to energize the magnet an additional electro-magnetic force must be applied to the circuit.

I prefer to utilize the coin only to impart the initial movement to the disk 40 and to complete this movement by a direct connection between the arm 28 and a part permanently secured to the disk. When the coin is engaged by the arm 28 it is moved around the pin or projection 39 and caused to engage a second projection 50 secured to the disk 40 on substantially the same radius with the projection 39. In the present instance the disk is adapted to rotate through a quarter revolution upon each operation thereof and there are four of the projections 50 and four of the projections 39 spaced equal distances apart about the face of the disk. The projections 50 are shown in the nature of teeth projecting from a disk or plate 51 rigidly secured to, and, if desired, formed integral with the disk 40. The space

between the projections 50 and 39 is insufficient to permit the coin to pass between them and, consequently, the disk and the shaft 41 will be rotated. Mounted on a stud carried by the shaft 41 and rotating with the disk 40 is a plate 52 having four projections or teeth 53, as shown in Fig. 2. Mounted upon the arm 28 is a projection 54 which is so arranged with relation to the teeth 53 of the plate 52 that when the disk 40 and plate 52 have been rotated through a partial revolution by the coin one of the teeth 53 will be moved into the path of the projection 54 and will be engaged thereby, thus forming a direct connection between the disk and the arm 28 and causing the disk to complete its movement through ninety degrees of a revolution. The shape of the projections or teeth 53 are such that when the disk 40 has completed an operative movement and is in its normal position the tooth following the tooth just acted upon by the arm 28 will lie out of the path of the projection carried by that arm, thus permitting the arm to return to its idle position without engaging any part connected with the disk. Further, this arrangement of the teeth permits the arm 28 to be moved through its full stroke without affecting the position of the disk unless there is a coin interposed between the arm and the stops on the disk. Thus, should the arm be actuated accidentally or by mistake the record will not be affected. In this manner the collector is protected against incompetent or careless operators at the central station. The direct engagement between the tooth of the plate 52 and the arm 28 releases the pressure on the coin which has by this time been moved over a branch chute 55 and permits the coin to drop through said branch chute into the coin receptacle 37.

In order to restore the operative connection between the catch 10 and the lever 16 after the coin has been deposited in the receptacle means are provided for rocking the lever 6 about its axis to cause the arm 9 to again engage the catch. To this end the lever is projected beyond the roller 8 and has a portion 56 lying in the path of a projection or roller 47 on a lever 48 pivotally supported on the axis of the armature 44 and having a portion 49 extending across the armature, provided with lips arranged on opposite sides of the axis of the armature and adapted to be actuated when the armature moves in either direction. Consequently, when the armature is actuated in a direction to release the spring the projection 47 will engage the portion 56 of the lever 6 and will move the lever about its axis to re-engage the arm 9 and catch 10. This movement also carries the roller 8 out of engagement with the contact member 5 and in order that the contact members may not sep-

arate and break the circuit before the several parts have completed their movements the upper end of the contact member 5 is provided with a recess 46 within which, 5 when the parts are in their normal positions, the projection 47 will lie, thus permitting the contact member to move away from its coöperating member 4 to break the circuit. However, the upward movement of 10 the lever 48 will cause the projection to move out of the recess and engage the adjacent portion of the contact member 5, thus holding that member against movement away from its coöperating contact member 15 and maintaining the circuit through the magnets. In addition to insuring that the magnets will be energized for a time sufficient to allow the several parts to complete their movements the above device for main- 20 taining the contact members in engagement also eliminates the sparking of these contact members, as it makes it necessary for the circuit to be broken first at the central station. Consequently, when the contact 25 members 4 and 5 are separated the circuit is dead and there is no spark. This is im- portant because the sparking decreases the efficiency of the contact points and in isolated stations it is difficult to keep the points 30 in a condition to provide a good contact if there is any sparking.

If the central operator is unable to make the connection requested by the calling party the coin is, as above stated, returned 35 to that party. To accomplish this I provide means whereby the stop 12 on the detent lever may be moved a distance sufficient to permit the coin to pass between it and the pin 39 on the disk and to enter a branch 40 chute 57 leading to a cup 58^a at the front of the machine where the coin can be recovered by the party who deposited it. In order that this movement may be imparted to the stop 12, I have mounted the same on 45 the lower end of the lever 58 which is mounted on the same center, 7, on which the lever 6 is mounted. The lever 58 has an arm 59 connected by a pin and slot connection with a lever 60 which is pivotally 50 mounted on the axis of the pivoted armature 44 and has a part, indicated at 61, projecting over that end of said armature opposite the end which is adapted to operate the lever 34 to release the spring 31. 55 Consequently, when the coil of the magnet is energized and the adjacent end of the armature drawn down the opposite end will be elevated and will engage the part 61 of the lever 60 and through its connection with 60 the lever 58 will move the latter and the stop 12 in a direction to move the stop toward the end of the slot 13 and increase the distance between the same and the pin 39. In order to restore the operative relation 65 between the catch and the arm 9 of the

lever 6 when the coin is thus returned the lever 6 has a finger 62 arranged in the path of the end of the lever 60, and the movement of this lever to release the coin also moves the lever 6 in a direction to cause the 70 arm 9 to again engage the catch 10.

As above stated any suitable counting mechanism may be employed and, in the present instance, I have utilized a well known form of counter comprising a series 75 of alined counter wheels, as indicated at 63, and provided with the usual transfer mechanism which, in the present instance, is mounted on a shaft 64. Inasmuch as this counting mechanism is well known it is not 80 deemed necessary to here describe and show the same in detail. Suffice it to say that the units counter is provided with a gear 65 which meshes with a gear 66 on the transfer shaft 64. The transfer mechanism is loosely 85 mounted on the shaft 64 and this enables me to utilize this shaft as a driving shaft for the counters by rigidly securing the gears 66 thereto. The transfer shaft 64 also has secured thereto a gear 67 which meshes 90 with a gear 68 on the shaft 41, which latter shaft has secured thereto a second gear 70 which meshes with a gear 71 secured to the disk 40. This latter gear may be attached to the disk in any suitable manner but as 95 here shown it comprises an annular flange secured to the rear face of the disk and pro- vided on its outer periphery with teeth con- stituting the gear 71 and on its inner face with projections 72 constituting ratchet 100 teeth, and coöperating with a pawl 73 to hold the disk and the connected mechanism against reverse movement. The ratio of the gearing is such that a quarter rotation of the disk 40 will advance the units counter 105 wheel of the counter a distance sufficient to register the value of the coin. The counter wheels 63 are preferably so mounted that they can be reset to zero and to this end each counter has secured thereto a pawl 74 110 adapted, when registering movement is im- parted to the counter wheel, to move over the counter shaft which has a longitudinal notch 76. When it is desired to reset the mechanism the counter shaft is rotated and 115 the notch in the shaft picks up the several pawls and counter wheels and brings them to zero position. In order, however, that the counter wheels may be rotated is is necessary that they should be disconnected 120 from the driving mechanism, which mecha- nism is locked against movement. I have, therefore, mounted the counter shaft in arms 77 which are pivotally mounted on a shaft 78 and are so arranged that when 125 moved about their axes the counter wheels will be carried toward or away from the transfer mechanism. In order to maintain a check upon the operation of the machine I prefer to provide a total counter which is 130

never reset and which will indicate the total amount of money which has been deposited in the machine. Thus by noting the difference between the present indication on the 5 total counters and the last previous record taken therefrom the amount of money received in the interval can be ascertained. As here shown a second group of counter wheels 79 are mounted immediately in the 10 rear of the counter 63 and are driven from a gear 80 on the shaft 41 in the same manner that the counter wheels 63 are driven. These total counters are provided with transfer mechanism as are the detail 15 counters.

To enable a more complete check to be kept from the collections made from the various stations I prefer to provide each machine with means for taking a record from 20 both the detail and total counters. This record may be taken in any suitable manner and, in the present instance, I have shown the counter wheels as comprising type wheels and have provided means for printing a record from the wheels onto a slip of 25 paper. The type wheels may be inked in any desired manner but I have here shown an inking ribbon 81 extending about the counting mechanism and guided on rollers 30 82. One of these rollers 82 has a gear 83 meshing with a gear 84 on the shaft 78, which gear is connected by an intermediate gear 85 with a gear 86 on the detail counter shaft. Thus, each operation of the detail 35 counter shaft to reset the counters will impart movement to the roller 83 and advance the ribbon. It is preferable that means should be provided whereby a record must necessarily be printed before access can be 40 had to the money receptacle and I have, in the present instance, so arranged the printing mechanism that the act of opening the door 87 leading to the money receptacle will operate the printing devices to take a record 45 from the counters. In the present arrangement of the device I have provided a platen 88 adapted to engage such type of the two counters as are in printing position. This platen is carried by a swinging plate 89 piv- 50 otally mounted at its rear edge, as shown at 90. Preferably, the platen is adjustable on the plate by means of screws 91 to enable the impression to be regulated. The plate is swung about its axis to cause the same to 55 move toward or away from the platen by means of a lever 91 having a projection 92 arranged to engage the forward portion of the plate 89. This lever is loosely mounted on a shaft 93 and connected with the plate 60 89 by a spring 94. When the movement of the lever 91 is unrestricted it will move about its axis until the plate rests upon the shaft 93. The lower arm of the lever 91 has a projection 95 arranged adjacent to the 65 edge of an inwardly extending plate or arm 96 rigidly secured to the door 87 and moving therewith. The length of the lever 91 is such that the projection 95 will just clear the curved edge of the arm 96 but this edge is provided with a cam surface, such as a 70 projection 97, which, when the door is moved in either direction, will engage the projection 95 and rock the lever about its axis. When the door is closed the projection 95 on the arm will lie in front of the projection 75 97 and upon the outward movement of the door the projection 97 will rock the lever 91 in a direction to move the platen toward the type wheels, thus causing the paper which rests upon the platen to be pressed against 80 the ribbon and an impression taken from the type wheels. When the door is closed the lever 91 will be rocked in the opposite direction and no impression will be taken from the wheels. The projection 97 is arranged 85 so close to the door 87 that the printing mechanism will be operated before the door is opened far enough to permit access to be had to the money receptacle. This door also controls the resetting of the detail counters, 90 so that they cannot be reset until after a record has been printed therefrom. To this end one of the supporting arms 77 for the counter shaft is provided with a downwardly extending portion 98 having a roller 99 at its lower end adapted to ride over the curved surface of the arm 96 carried by the door. So long as the roller 99 is in engagement with the arm 96 the counter wheels 95 will be held in engagement with the transfer mechanism and will be locked against resetting movement, but when the end of the arm has passed the roller the counter wheels may be moved downward to permit of their 100 rotation. I prefer that the counter wheels 105 should be held normally in engagement with the transfer mechanism by means of a spring 100 and have provided means whereby the first movement of the resetting shaft to reset the counter wheels will move the latter out of engagement with the transfer mechanism. This mechanism comprises a 110 cam 101 secured to the resetting shaft and co-operating with a second cam 102 mounted on a fixed part of the machine, such as the transfer shaft and held against rotation. The two cams have recessed portions which lie adjacent one to the other when the counter wheels are in their normal position. When the counter shaft is rotated the recessed portions are moved out of alignment and the wider portions of the cams come 115 into engagement and force the counter wheels downward. As soon as the resetting movement is completed the counter wheels are returned to their operative positions. The paper may be fed to the platen in any suitable manner but I prefer that it should be in the form of slips or sheets, one of which 120 will be placed in position on the platen by 125 130

the collector each time he collects the money from the station. Upon opening the door to make the next collection a record will be printed upon this slip and this record is removed and turned in at the office with the money collected and a new slip placed on the platen. These record slips not only indicate the amount of each collection but they also are marked to indicate the grand total of all the registrations at this station so that by a comparison of a given slip with the last previous slip on file it is easy to ascertain whether or not said slip is the only slip which has been printed since the printing of said previous slip. If desired, an electro-type may be provided, as indicated at 105, to print on the slip the number of the station or instrument, thereby identifying each slip with the particular station where it was printed.

The operation, together with the purposes and advantages of the same, have been clearly set forth in the foregoing description of the several parts of the mechanism and it will be understood that while I have shown and described one embodiment of the invention, this has been chosen for the purposes of illustration only and I do not desire to be limited to the details of construction, for obvious modifications will occur to a person skilled in the art.

Having thus fully described my invention, what I claim as new and desire to secure by Letters Patent, is:—

1. In a mechanism of the character described, the combination, with a counter and power mechanism to actuate the same, of a device to actuate a calling signal, a manually actuated device to control the operation of said signal actuating device, and means operated by said manually actuated device to put said power mechanism in condition to operate said counter.

2. In a mechanism of the character described, the combination, with a counter, and a spring to actuate the same, of a device to actuate a calling signal, a manually actuated device to control said signal actuating device, and means operated by said manually actuated device to put said spring under tension.

3. In a mechanism of the character described, the combination, with a counter, and a spring to actuate the same, of a signaling device, a coin chute, a device arranged to be actuated by a coin after it has been deposited in said chute to permit the operation of said signaling device, a device arranged to normally prevent the deposit of a coin in said chute, means to move said device into an inoperative position, and mechanism actuated by said means to place said spring under tension.

4. In a mechanism of the character de-

scribed, the combination, with a counter, and a spring to actuate the same, of a signaling device, a coin chute, a device arranged to be actuated by a coin after it has been deposited in said chute to permit the operation of said signaling device, a device arranged to normally prevent the deposit of a coin in said chute, a lever to move said device into an inoperative position, and connections between said lever and said spring whereby the movement of the lever in one direction will place said spring under tension.

5. In a mechanism of the character described, the combination, with a counter, and a spring to actuate the same, of a signaling device, a coin chute, a device arranged to be actuated by a coin after it has been deposited in said chute to permit the operation of said signaling device, a cut-off extending normally across said chute to prevent the insertion of a coin, a lever carrying said cut-off, and a manually operated lever connected with the first-mentioned lever, a connection between said manually operated lever and said spring, whereby the operation of the manually operated lever will cause said spring to be placed under tension.

6. In a mechanism of the character described, the combination, with a counter, and a spring to actuate the same, of a signaling device, a coin chute, a device arranged to be actuated by a coin after it has been deposited in said chute to permit the operation of said signaling device, a cut-off extending normally across said chute to prevent the insertion of a coin, a lever carrying said cut-off, a manually operated lever connected with the first-mentioned lever, a connection between said manually operated lever and said spring, whereby the operation of the manually operated lever will cause said spring to be placed under tension, and means to maintain said spring under tension after said manually operated lever has been released.

7. In a machine of the character described, the combination, with a counter, an actuating device therefor, and a spring connected with said actuating device to impart operative movement thereto and adapted to be placed under tension by the movement of said device in one direction, of a signaling device, manually actuated means to control the operation of said signaling device, and a connection between said manually actuated device and said actuating device to impart movement to the latter in a direction to place said spring under tension.

8. In a machine of the character described, the combination, with a counter, an actuating device therefor, and a spring con-

5 nected with said actuating device to impart operative movement thereto and adapted to be placed under tension by the movement of said device in one direction, of a signaling device, manually actuated means to control the operation of said signaling device, a connection between said manually actuated device and said actuating device to impart movement to the latter in a direction to 10 place said spring under tension, and means to lock said actuating device in a position to retain said spring under tension.

9. In a machine of the character described, the combination, with a counter, an 15 actuating device therefor, and a spring connected with said actuating device to impart operative movement thereto and adapted to be placed under tension by the movement of said device in one direction, of a signaling device, manually actuated means to control the operation of said signaling device, a connection between said manually actuated device and said actuating device to impart movement to the latter in a direction 20 to place said spring under tension, means to lock said actuating device in a position to retain said spring under tension, and means under the control of the central operator for releasing said actuating device to permit it to operate said counter 25

10. In a machine of the character described, the combination, with a counter, an actuating device therefor, and a spring connected with said actuating device to impart 30 operative movement thereto and adapted to be placed under tension by the movement of said device in one direction, of a coin chute, a signaling device, a device arranged in a position to be actuated by a coin after it 35 has been deposited in said chute to permit the operation of said signaling device, a movable member to control the insertion of the coin in said chute, and a connection between said member and said spring to place 40 said spring under tension when said member is actuated to permit a coin to be inserted in the slot.

11. In a machine of the character described, the combination, with a counter, an 50 actuating device therefor, and a spring connected with said actuating device to impart operative movement thereto and adapted to be placed under tension by the movement of said device in one direction, of a coin chute, a signaling device comprising a movable contact member, a spring-actuated lever adapted to impart movement to said movable member, a detent for holding said lever in an inoperative position, said detent 55 having a part extending into the path of the coin after it has been deposited in said chute and adapted to be actuated thereby to release said spring-actuated lever, a manually operated device to control the in- 60

65 sertion of the coins in said chute, and an operative connection between said manually operated member and said actuating device, whereby the movement of the former to permit a coin to be deposited in the chute will place said spring under tension. 70

12. In a machine of the character described, the combination, with a counter, an actuating device therefor, and a spring connected with said actuating device to impart operative movement thereto and adapted to be placed under tension by the movement of said device in one direction, of a coin chute, a signaling device comprising a movable contact member, a spring-actuated lever adapted to impart movement to said movable member, a detent for holding said lever in an operative position, said detent having a part extending into the path of the coin after it has been deposited in said chute and adapted to be actuated thereby to release said spring-actuated lever, a cut-off to close said chute against the insertion of coins, a manually operated lever connected with said cut-off, and a connection between said manually operated lever and said actuating device whereby the movement of said lever to open said chute will place said spring under tension. 80

13. In a machine of the character described, the combination, with a counter, an actuating device therefor, and a spring connected with said actuating device to impart operative movement thereto and adapted to be placed under tension by the movement of said device in one direction, of a coin chute, a signaling device comprising a movable contact member, a spring-actuated lever adapted to impart movement to said movable member, a detent for holding said lever in an inoperative position, said detent having a part extending into the path of the coin after it has been deposited in said chute and adapted to be actuated thereby to release said spring-actuated lever, a cut-off to close said chute against the insertion of coins, a manually operated lever connected with said cut-off, a connection between said manually operated lever and said actuating device whereby the movement of said lever to open said chute will place said spring under tension, a device to lock said actuating device in a position to maintain the tension on said spring, and means to return said lever and said cut-off to their normal positions. 110

14. In a machine of the character described, the combination, with a counter, an actuating device therefor, and a spring connected with said actuating device to impart operative movement thereto, of a movable member operatively connected with said counter and having a stop, means coöperating with said stop to support a coin in 125

engagement with said stop and in the path of said actuating device, whereby when said actuating device is operated by said spring said coin will impart the initial movement to said movable member.

15. In a machine of the character described, the combination, with a counter, an actuating device therefor, and a spring connected with said actuating device to impart operative movement thereto, of a movable member operatively connected with said counter and having a stop, means coöperating with said stop to support a coin in engagement with said stop and in the path of said actuating device, whereby when said actuating device is operated by said spring said coin will impart the initial movement to said movable member, and a part carried by said movable member adapted to be engaged by said actuating device to form a direct connection between said parts after the initial movement has been imparted to said movable member.

16. In a machine of the character described, the combination, with a counter, an actuating device therefor, and a spring connected with said actuating device to impart operative movement thereto, of a signaling device, a coin chute, a device to control the operation of said signaling device having a part arranged to be engaged by a coin after it has been deposited in said chute, a movable member operatively connected with said counter and having a part coöperating with the part first engaged by said coin to support the coin in the path of said actuating member, whereby the operative movement of said actuating device will cause said coin to impart the initial movement to said movable member.

17. In a machine of the character described, the combination, with a counter, an actuating device therefor, and a spring connected with said actuating device to impart operative movement thereto, of a signaling device, a coin chute, a device to control the operation of said signaling device having a part arranged to be engaged by a coin after it has been deposited in said chute; a movable member operatively connected with said counter and having a part coöperating with the part first engaged by said coin to support the coin in the path of said actuating member, whereby the operative movement of said actuating device will cause said coin to impart the initial movement to said movable member, a part secured to said movable member adapted to be carried into the path of said actuating device, by the initial movement of said movable member, to form a direct connection between said actuating device and said disk.

18. In a machine of the character described, the combination, with a counter, an actuating device therefor, and a spring con-

nected with said actuating device to impart operative movement thereto and adapted to be placed under tension by the movement of said device in one direction, of a signaling device, a spring-actuated lever to cause the 70 operation of said signaling device, a coin chute, a detent to hold said lever in inoperative relation with said signaling device, said detent arranged to be engaged by a coin deposited in said chute to release said lever, 75 a movable member operatively connected with said counter and having a part coöperating with a part carried by said detent to support said coin in a position to be engaged by said actuating device, a manually operated lever to control the admission of coins to said chute, a connection between said manually operated lever and said actuating device, whereby when said lever is manipulated to permit a coin to be inserted in the 80 chute said spring will be placed under tension, and means under the control of the central operator to release said actuating device to permit it to be moved by said spring into engagement with said coin to impart 85 movement to said movable member.

19. In a machine of the character described, the combination, with a counter, an actuating device therefor, and a spring connected with said actuating device to impart 90 operative movement thereto and adapted to be placed under tension by the movement of said device in one direction, of a signaling device, a spring-actuated lever to cause the 95 operation of said signaling device, a coin 100 chute, a detent to hold said lever in inoperative relation with said signaling device, said detent being arranged to be engaged by a coin deposited in said chute to release said lever, a movable member operatively connected with said counter and having a part coöperating with a part carried by said 105 detent to support said coin in a position to be engaged by said actuating device, a manually operated lever to control the admission 110 of coins to said chute, a connection between said manually operated lever and said actuating device, whereby when said lever is manipulated to permit a coin to be inserted in the chute said spring will be placed under 115 tension, means under the control of the central operator to release said actuating device to permit it to be moved by said spring into engagement with said coin to impart movement to said movable member, and a 120 part secured to said movable member and arranged to be moved into a position to be engaged by said actuating device by the initial movement of said movable member.

20. In a device of the character described, 125 a counter, a movable member operatively connected with said counter, and a spring-operated actuating device, of means including a coin for establishing a connection between said movable member and said actu- 130

ating device, and means to release said actuating device to cause movement to be imparted to said movable member.

21. In a device of the character described, 5 a counter, a movable member operatively connected with said counter, and a spring-operated actuating device, of means including a coin for establishing a connection between said movable member and said actuating device whereby the movement of said actuating device will impart initial movement to said movable member, other means for establishing a direct connection between said actuating device and said movable 10 member after initial movement has been imparted to said movable member, and means to release said actuating device to cause movement to be imparted to said movable member.

22. In a device of the character described, 20 the combination, with a counter, and a spring-actuating device for said counter, of a rotatable disk operatively connected with said counter, a stop carried by said disk, and 25 means coöperating with said stop to support a coin in a position to establish a connection between said actuating device and said rotatable disk whereby the movement of said actuating member will impart initial 30 movement to said disk.

23. In a device of the character described, 35 the combination, with a counter, and a spring-operated actuating device for said counter, of a rotatable disk operatively connected with said counter, a stop carried by said disk, and means coöperating with said stop to support a coin in a position to establish a connection between said actuating device and said rotatable disk whereby the 40 movement of said actuating member will impart initial movement to said disk, and a part connected to and rotatable with said disk and so arranged that the initial movement of said disk will move said part into 45 a position to be engaged by said actuating device, thereby forming a direct connection with said actuating device to complete the movement of said disk.

24. In a device of the character described, 50 the combination, with a counter, and a spring-operated actuating device for said counter, of a coin chute, a stop arranged adjacent to said coin chute and adapted to be engaged by a coin passing through the same, 55 a rotatable disk having a stop arranged to coöperate with the first-mentioned stop to support said coin in the path of said actuating device, a second stop carried by said disk and coöperating with the first stop on 60 said disk to limit the movement of said coin relatively thereto when the coin is engaged by said actuating device.

25. In a device of the character described, 65 the combination, with a counter, and a spring-operated actuating device for said

counter, of a coin chute, a stop arranged adjacent to said coin chute and adapted to be engaged by a coin passing through the same, a rotatable disk having a stop arranged to coöperate with the first-mentioned stop to 70 support said coin in the path of said actuating device, a second stop carried by said disk and coöperating with the first stop on said disk to limit the movement of said coin relatively thereto when the coin is engaged by said actuating device, and another part secured to said disk and adapted to be engaged by said actuating device after the initial movement has been imparted to said disk. 75

26. In a device of the character described, the combination, with a counter, and a spring-operated actuating device for said counter, of a rotatable disk having a plurality of stops spaced equal intervals about 80 the same, a chute leading to a point adjacent to said disk, a part arranged to coöperate with one of said stops to support a coin in the path of said actuating device, and a second series of stops arranged to coöperate 85 with the stops of the first series to limit the movement of said coin relatively to said disk when the coin is engaged by said actuating device.

27. The combination, with a main frame 95 having a coin chute, a counter, a movable member operatively connected with said counter, and a spring-operated actuating device for said counter, of means to support a coin in position to establish a connection between said actuating device and said movable member, and means to either release said actuating device to permit it to actuate said movable member or to cause said coin to be discharged. 100

28. The combination, with a main frame, 105 having a coin chute, a counter, a movable member operatively connected with said counter, and a spring-operated actuating device for said counter, of a stop carried by 110 said movable member, a second stop movably supported adjacent to the first-mentioned stop and coöperating therewith to support a coin in the path of said actuating device, whereby the movement of the latter will cause said coin to impart movement 115 to said movable member, and means for imparting bodily movement to said movable stop to release said coin and permit it to be discharged. 120

29. In a device of the character described, the combination, with a casing having a coin chute and a coin receptacle, a cut-off for said chute, a counter to register the coin deposited in said receptacle, and a spring-actuated device for operating said counter, said device being controlled by the movement of said cut-off into an inoperative position. 125

30. In a device of the character described, 130

a signaling device, means to control the operation of said signaling device, a coin receptacle, a counter to register the coins deposited in said receptacle, a spring-operated device for actuating said counter, and an operative connection between said spring-operated device and the controlling means for said signaling device, whereby the spring of the former will be placed under tension when said signaling device is operated.

31. In a device of the character described, the combination, with a casing, a coin chute, a coin receptacle, a counter, a spring-operated device to actuate said counter to register the coins deposited in said receptacle, means to support a coin in a position to establish a connection between said counter and said actuating device, and a second chute leading to the exterior of said casing, of means to permit said spring-operated device to impart movement to said coin to actuate said counter and to deposit said coin in said receptacle or to cause said coin to be discharged through said second chute.

32. In a device of the character described, the combination, with a casing, a coin chute, a coin receptacle, a counter, a spring-operated device to actuate said counter to register the coins deposited in said receptacle, means to support a coin in a position to establish a connection between said counter and said actuating device, and a second chute leading to the exterior of said casing, of a controlling device, the movement of which in one direction will discharge said coin through said second chute and the movement of which in the other direction will permit said spring-operated device to actuate said counter and deposit said coin in said receptacle.

33. In a device of the character described, the combination, with a casing, a coin chute, a coin receptacle, a counter, a spring-operated device to actuate said counter to register the coins deposited in said receptacle, means to support a coin in a position to establish a connection between said counter and said actuating device, and a second chute leading to the exterior of said casing, of a polarized magnet having a pivoted armature, the movement of which in one direction will cause said spring-operated device to actuate said counter and deposit said coin in said receptacle and the movement of which in the other direction will cause said coin to be discharged through said second chute.

34. In a device of the character described, the combination, with a signaling device comprising a movable contact member, a counter, a spring-actuated lever to impart movement to said contact member to operate said signaling device, a coin-actuated detent to hold said spring-pressed lever in an in-

operative position, of a counter, a spring-operated device for actuating said counter, and an electro-magnet to control the operation of said spring-operated device, and means actuated by said magnet to cause said detent to engage said lever and to retain said movable contact member in its operative position.

35. In a device of the character described, the combination, with a signaling device comprising a movable contact member, a spring-actuated lever, a part having one arm adapted to actuate said contact member, a detent adapted to engage the other arm of said lever to hold said lever normally in an inoperative position relatively to said contact member, and means for releasing said detent, of a counter, a device for actuating said counter, an electro-magnet for controlling said actuating device, a lever arranged to be actuated by said magnet and having means to actuate the first-mentioned lever to restore the connection between the same and said detent and to retain said contact member in its operative position.

36. In a device of the character described, the combination, with a casing, a counter, a movable member connected with said counter, a spring-operated actuating device for said counter, and a stop coöperating with said movable member to support a coin in a position to establish a connection between said spring-operated device and said counter, of means for imparting bodily movement to said stop to release said coin, and a chute to receive the coin so released and discharge the same from said casing.

37. In a device of the character described, the combination, with a casing, a counter, a movable member connected with said counter, a spring-operated actuating device for said counter, a lever, a stop mounted on said lever and coöperating with said movable member to support a coin in a position to establish an operative connection between said spring-operated device and said counter, of an electro-magnet comprising an armature, and an operative connection between said armature and said lever whereby the movement of said armature will move said lever in a direction to cause said stop to release said coin, and a chute to receive said coin and discharge the same from said casing.

38. In a device of the character described, a casing, a signaling device comprising a movable contact member, a lever to operate said movable contact member, a detent to hold said lever normally in an inoperative position, a second lever supporting said detent, a counter, a movable member connected with said counter, a spring-operated device for actuating said counter, a stop connected with said detent and arranged to coöperate with said movable member to support a coin

in a position to establish an operative connection between said spring-operated device and said counter, of an electro-magnet, and means controlled by said magnet to permit 5 said spring-operated device to actuate said counter, and other means controlled by said magnet to impart bodily movement to said detent and the stop carried thereby to release said coin, and a chute arranged to receive 10 the coin so released and discharge the same from said casing.

39. In a device of the character described, a casing, a signaling device comprising a movable contact member, a lever to operate 15 said movable contact member, a detent to hold said lever normally in an inoperative position, a second lever supporting said detent, a counter, a movable member connected with said counter, a spring-operated device 20 for actuating said counter, a stop connected with said detent and arranged to coöperate with said movable member to support a coin in a position to establish an operative connection between said spring-operated device 25 and said counter, said stop being so arranged that when engaged by a coin it will actuate said detent to release the actuating lever for said contact member, of an electro-magnet comprising an armature having 30 movement in two directions, a connection between said armature and the lever carrying said detent to cause the movement of said armature in one direction to actuate said lever to move said stop in a direction

to release the coin and to also restore the 35 connection between said detent and the lever for actuating said contact member, and other means actuated by the same movement of said armature to retain said actuating member in its operative position when said 40 connection has been restored.

40. In a registering device for telephone pay stations, the combination, with a counter, and power mechanism to actuate the same, of a device to actuate a calling 45 signal, a manually actuated device to control the operation of said signaling device, means operated by said manually actuated device to put said power mechanism in condition to actuate said counter, and means 50 controlled by the central operator to cause the operation of said power mechanism.

41. In a registering device for telephone pay stations, the combination, with a counter, and a spring to actuate the same, 55 of a device to actuate a calling signal, a manually operated device to control said actuating device, means operated by said manually operated device to put said spring under tension, and means controlled by the 60 central operator to release said spring.

In testimony whereof, I affix my signature in presence of two witnesses.

MAXIMILIAN M. GOLDBERG.
